(57) **CLAIM**

The ornamental design for a flip phone case wallet, as shown and described.

DESCRIPTION

FIG. 1 is a front perspective view of the flip phone case wallet showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof when the flip phone case wallet is folded.

The dash-dash broken lines show portions of the flip phone case wallet that form no part of the claimed design. The dot-dash broken line represents stitching that forms a part of the claimed design.
